Primary Examiner — Doris Clark

(21) Appl. No.: **29/395,911**

(57) **CLAIM**

(22) Filed: **Apr. 20, 2012**

We claim the ornamental design for a fence post brace, as shown and described.

(51) **LOC (10) Cl.** 25-01

DESCRIPTION

(52) **U.S. Cl.**

USPC **D25/133**

(58) **Field of Classification Search**

USPC D25/133; 52/155, 146; 256/35, 34,
256/65.01; 248/508, 510; 404/6, 59

See application file for complete search history.

(56) **References Cited**

FIG. 1 is a top perspective view of a fence post brace.
FIG. 2 is a side elevation view thereof showing environmental structure; and,

FIG. 3 is an enlarged view of the fence post brace.
Broken lines are included for the purpose of illustrating portions of the combination fence brace article and/or environmental structure that form no part of the claimed design.
